TRAFFIC PROTECTION APPARATUS

Howard A. Thompson, Edgewood, Pa., assignor to
 The Union Switch & Signal Company, Swiss-
 vale, Pa., a corporation of Pennsylvania

Application May 22, 1947, Serial No. 749,833

13 Claims. (Cl. 246—219)

1

My invention relates to traffic protection apparatus, and particularly to apparatus for providing protection for trains moving over a stretch of railway which includes manually operable track switches, such as in turnouts or in crossovers.

In order to provide such protection, various arrangements have been devised in which a manually operable switch lever is arranged for manually moving each switch, and in which a manually operable auxiliary lever is arranged for mechanically locking each turnout switch or each pair of crossover switches when the auxiliary lever is in its normal position.

One feature of my invention is the provision of an electric lock for each switch lever, which, when deenergized, locks its switch lever when its switch lever is in the normal position, and the electric lock, if not in its locking position, prevents return of an associated auxiliary lever from its reverse to its normal or locking position. Each auxiliary lever, at the beginning of an operation from its normal to its reverse position, closes contacts associated with locking its switch lever or levers for shunting adjacent track circuits and, upon being restored to its normal position, mechanically locks the electric locks for its switch levers in their locking positions.

Another feature of my invention is the provision of time releasing means for an electric lock in which a stick relay has a pick-up circuit controlled by a checking back contact of a time element relay, and in which the electric lock is controlled by a circuit which includes a front contact of the stick relay in series with a front contact of the time element relay.

I shall describe three forms of apparatus embodying my invention, and shall then point out the novel features thereof in claims.

In the accompanying drawings, Fig. 1 is a diagrammatic view showing one form of apparatus embodying my invention, in which a switch lever is provided for each switch of a crossover track for manually moving the associated switch between its normal and reverse positions, and in which each switch lever is provided with an electric lock for locking its lever in the normal position, and in which an auxiliary lever, upon being operated to its normal position, mechanically locks the electric locks for the switch levers in their locking positions, and also in which each electric lock is controlled by a manually controllable time releasing arrangement including a time element relay and a stick relay having a pick-up circuit controlled by a checking back

2

contact of the time element relay; Fig. 2 is a diagrammatic view showing apparatus similar to that shown in Fig. 1, but arranged for a turnout switch and derail instead of for the two switches of a crossover track; Fig. 2a is a diagrammatic view showing an electric lock, such as shown in Figs. 1 and 2, when the electric lock is in its energized or non-locking position, while the auxiliary lever is in its reverse position; and Fig. 3 is a diagrammatic view showing a modified form of the apparatus of Fig. 1, in which an auxiliary lever mechanically locks the switches of a crossover track as well as locking the switch levers, and in which an electric lock for the auxiliary lever is controlled by a time releasing arrangement including a time element relay and a stick relay having a pick-up circuit controlled by a checking back contact of the time element relay.

Similar reference characters refer to similar parts in each of the views.

Referring first to Fig. 1, a stretch of railway is shown comprising two main tracks, designated by the reference characters 1T and 2T, interconnected by a crossover track, designated by the reference character 3T, through hand-operated switches 1W and 2W. Track 1T is divided by insulated joints 4 to form a section a—b which includes switch 1W. Track 2T is similarly divided by other insulated joints 4 to form a section c—d which includes switch 2W.

Section a—b is provided with a track circuit including a track relay 1R connected across the rails of track 1T adjacent one end of the section, and a suitable source of current, such as a battery 5, connected across the rails of track 1T adjacent the opposite end of the section. Section c—d is similarly provided with a track circuit including a relay, designated by the reference character 2R, connected across the rails of the section adjacent one end, and a battery 5 connected across the rails adjacent the opposite end of the section.

A signal 1S is shown adjacent the relay end of section a—b for governing traffic movements toward the left, as shown in the drawing, which I shall assume is the westbound direction. A second signal 2S is shown adjacent the relay end of section c—d for governing traffic movements in the opposite or eastbound direction. A portion of a control circuit for signal 1S is shown including a front contact of track relay 1R and terminal N of a suitable source of current. A portion of a control circuit for signal 2S is also shown including a front contact of track relay

2R and terminal N. Signals 1S and 2S may be of any suitable design such, for example, as the well-known searchlight type.

Switch levers 1V and 2V are shown for manually moving switches 1W and 2W, respectively, between their normal and reverse extreme positions. An auxiliary lever 3V is also shown between switch levers 1V and 2V. Each of the levers 1V, 2V and 3V has a normal position *n*, in which it is shown in the drawing, and a reverse position *r*.

Associated with each of the switch levers 1V and 2V are two lock bars designated by the reference characters 6 and 7. Each bar 6 is reciprocable between a normal position, in which it is shown, and a reverse position to the left, as shown in the drawing, by auxiliary lever 3V through a mechanical connection 8 which may be a pipe line. Bar 7 at switch 1W is reciprocable from a normal position, in which it is shown, to a reverse position to the left, as shown in the drawing, by switch lever 1V, and bar 7 at switch 2W is similarly operable by switch lever 2V.

Each of the bars 6 is provided with a blocking piece 9 for engagement with a lug 10 which is rigidly connected with the associated lever 1V or 2V. In this way, levers 1V and 2V are mechanically locked in their normal or *n* position by levers 3V in its normal position, and can be operated to the *r* position only after lever 3V has been placed in its *r* position, thereby removing the blocking pieces 9 from engagement with lugs 10.

A switch circuit controller 1L is operated in conjunction with bar 6 at lever 1V, and a second switch circuit controller 2L is operated in conjunction with bar 6 at lever 2V. Each of the circuit controllers 1L and 2L comprises contacts, designated 11 and 12, which become closed at the beginning of an operation of lever 3V to its reverse position, and which remain closed until the final portion of the return movement of lever 3V to its normal position.

Each of the bars 7, during the initial portion of the movement of its lever 1V or 2V to the reverse position, is withdrawn from locking engagement with a switch lock rod 13, and the subsequent portion of the movement of lever 1V or 2V to its reverse position moves switch 1W or 2W, respectively, to the reverse position.

Bars 6 and 7 associated with each of the switch levers are interlocked with each other by a lug 14 attached to bar 6 and a lug 15 attached to bar 7, so that if bar 6 is moved to the left, as shown in the drawing, by an operation of lever 3V to its *r* position, and if the associated bar 7 is then moved to the left by an operation of its switch lever, the auxiliary lever 3V can then not be returned to its *n* position until after the switch lever is returned to its *n* position.

The arrangement of bars 6 and 7, and the interlocking of auxiliary lever 3V with the switch levers by these bars is similar to the arrangement shown in Figs. 14 and 15 of Letters Patent of the United States No. 2,355,989 which was granted August 15, 1944, to Kenneth J. J. McGowan, for Slow Release Lock for Railway Switches. The arrangement in Figs. 14 and 15 of that patent is described on page 6 of the patent, beginning with line 47 of column 1.

Associated with levers 1V and 2V are electric locks having control windings 1K and 2K, respectively. Each of the windings 1K and 2K controls a locking armature 17, which, when its winding is deenergized while the associated switch

lever 1V or 2V is in its *n* position, falls into locking engagement with a locking segment 18 which is rigidly connected with the associated switch lever.

5 Armature 17 of each of the windings 1K and 2K is locked in its deenergized locking position by a plunger 16 when lever 3V is in its *n* position. Operation of each plunger 16 is by lever 3V, and may be effected through pipe line 8 and crank arms 19 and 20 each of which has a pivot point 21.

Padlocks, designated by the reference characters 1P and 2P, are provided for the electric locks for levers 1V and 2V, respectively. A bow 22 of each of these padlocks, upon being placed in the locking position in the lever latch of its electric lock, as shown in the drawing, opens a latch contact 23.

A lever circuit controller contact 24 is operated by lever 3V, and is arranged to be closed only when lever 3V is in its extreme reverse position *r*.

A stick relay TS has a pick-up circuit controlled by contact 24 of lever 3V and by a checking back contact of a time element relay TE, and has a stick circuit controlled by contact 24 of lever 3V. The time element relay, designated by the reference character TE, is controlled by a front contact of relay TS and by contact 24 of lever 3V. Electric lock windings 1K and 2K are controlled by front contacts of relays TS and TE in series and by contact 24 of lever 3V, and also by contact 23 operated by padlocks 1P and 2P, respectively.

Referring next to Fig. 2, a stretch of main rail-way track 1T is shown connected with an auxiliary or turnout track AT by a hand-operated switch 1W. A derail D, normally in the derailing position for track AT, is operated in conjunction with bar 7 associated with lever 1V.

40 Track 1T is divided by insulated joints 4 to form a section *a*—*b* including switch 1W. A track circuit is provided for this section which includes a relay 1R connected across the rails adjacent one end of the section, and a suitable source of current such as a battery 5 connected across the rails adjacent the other end of the section.

45 A switch lever 1V is shown for manually moving switch 1W between its normal and reverse positions, and an auxiliary lever 3V is shown associated with lever 1V, as in Fig. 1. A switch circuit controller 1L, having a contact 12 which is similar to the contacts 12 in Fig. 1, is operated in conjunction with lock bar 6, as in Fig. 1. Contact 25, shown in the circuits for relays TE and TS, may be operated by the switch circuit controller 1L, and will then be closed only when lock bar 6 reaches the extreme left-hand position. Instead of being operated by switch circuit controller 1L, contact 25 may be operated by a lever circuit controller, similarly to contact 24 in Fig. 1, and will then be closed only when lever 3V reaches its *r* position. The interlocking arrangement for levers 1V and 3V, and the control of armature 17 of lock winding 1K by lever 3V are as shown in Fig. 1. The control of lock winding 1K is also the same as shown in Fig. 1.

50 Referring now to Fig. 2a, the relative positions of locking plunger 16 and armature 17 of lock winding 1K are shown when winding 1K is energized and lever 3V is in its *r* position.

55 Referring finally to Fig. 3, the form of apparatus here shown differs from that shown in Fig. 1 in that auxiliary lever 3V is here provided with an electric lock and levers 1V and 2V do

not have electric locks; only one lock bar 26 is associated with each lever 1V and 2V; relays TE and TS are controlled by a contact operated by bow 22 of padlock 3P for the electric lock for lever 3V instead of by a lever contact; and the main tracks are shunted by contacts operated by bow 22 of padlock 3P.

Having described, in general, the arrangement of the various parts of apparatus embodying my invention, I shall now describe the circuits and operation in detail.

As shown in the drawings, all parts of the apparatus are in the normal condition, that is, each of the switches 1W and 2W is in the normal position for a train movement along main track 1T or 2T, respectively; levers 1V, 2V and 3V are in the normal position *n*; the bows of the padlocks 1P, 2P and 3P are in the locking position in the lever latches of the electric locks for levers 1V, 2V and 3V, respectively; electric lock windings 1K, 2K and 3K are deenergized; relays 1R and 2R are energized; relays TS and TE are deenergized; and signals 1S and 2S are displaying a proceed indication.

The portions of the control circuits shown for signals 1S and 2S are closed by contact 30 of relays 1R and 2R, respectively.

I shall assume that, with apparatus arranged as shown in Fig. 1, a train is to move over cross-over track 3T from one of the main tracks to the other. A trainman will therefore move lever 3V to its reverse position *r*. The first portion of the movement of lever 3V, just as it leaves its *n* position, closes contacts 11 and 12 of switch circuit controllers 1L and 2L by moving pipe line 8 to the left, as is shown in the drawing. A shunt path is closed across section *a*—*b* through contact 12 at switch 1W, and a second shunt path is closed across section *a*—*b* through contact 12 at switch 2W. A shunt is also connected across the rails of section *c*—*d* through contact 11 at switch 1W, and a second shunt is connected across the rails of section *c*—*d* through contact 11 at switch 2W. Because of these shunts across sections *a*—*b* and *c*—*d*, relays 1R and 2R will be deenergized, and hence their front contacts 30 will open the circuits for signals 1S and 2S, causing these signals to display the stop indication.

Further movement of pipe line 8 to the left by lever 3V moves blocking piece 9 of each lock bar 6 out of locking engagement with lug 10 of the associated switch lever 1V or 2V. At the same time, pipe line 8, through cranks 19 and 20, withdraws each locking plunger 16 out of locking engagement with armature 17 of the associated electric lock winding 1K or 2K.

At the completion of the movement of lever 3V to its *r* position, lever contact 24 is closed. Contact 24, upon becoming closed, completes a circuit for energizing relay TS, this circuit passing from a suitable source of current such as a battery Q, through contact 24, back contact 31 of time element relay TE, and the winding of relay TS, back to battery Q. Relay TS, upon becoming energized, completes its own stick circuit, which is the same as the pick-up circuit just traced except that it includes contact 32 of relay TS instead of contact 31 of relay TE. Relay TS, upon becoming energized, also completes a circuit for energizing time element relay TE, this circuit passing from battery Q, through contact 24, contact 33 of relay TS, and the winding of relay TE, back to battery Q.

Upon his completion of the movement of lever 3V to its *r* position, the trainman will go to one of

the switches, 1W for example, and will remove bow 22 of padlock 1P from the lever latch of its electric lock, thereby effecting the closing of contact 23. Upon the lapse of a measured period of time, as determined by time element relay TE, contact 34 of relay TE will complete a circuit for energizing winding 1K, this circuit passing from battery Q, through contact 24 of lever 3V, contact 33 of relay TS, contact 34 of relay TE, contact 23 controlled by padlock 1P, and electric lock winding 1K, back to battery Q. Winding 1K will thereupon lift its armature 17 out of locking engagement with locking segment 18 of lever 1V.

The trainman will then move lever 1V to its *r* position. Lever 1V, during the initial portion of this movement to its *r* position, will withdraw its lock bar 7 to the left, as shown in the drawing, out of the notch shown in lock rod 13 for switch 1W, thereby unlocking switch 1W. Further movement of lever 1V moves switch 1W to its reverse position. The trainman will then go to switch 2W and will similarly reverse it.

By use of the time element relay TE for controlling energization of the electric locks, movement of switches 1W and 2W to the reverse position is prevented until a measured period of time has elapsed after signals 1S and 2S have been caused to display the stop indication. If a train were approaching signal 1S or signal 2S, it could therefore be stopped at signal 1S or at signal 2S if it were a sufficient distance in the rear of the signal at the time the signal was caused to display the stop indication, or if the train were too near to be stopped at signal 1S or 2S, it would have passed over switches 1W and 2W, before the electric locks could be energized to permit switches 1W and 2W to be moved to the reverse position. In this way, operation of switches 1W and 2W is prevented at times when it might be unsafe because of a train approaching signal 1S or signal 2S.

Use of the relay TS for controlling relay TE prevents movement of switches 1W and 2W before the given measured period of time has elapsed after signal 1S or signal 2S has been caused to display the stop indication, if relay TE has failed to return to its normal condition after previous energization. If relay TE had not previously returned all the way to its normal condition, then, if it were energized by a circuit which included only contact 24 of lever 3V, it might close its contact 34 in less than the given measured period of time and thereby permit switches 1W and 2W to be moved to the reverse position in less than the given measured period of time after signal 1S or signal 2S had been caused to display the stop indication.

I shall assume further that, after the train has moved over track 3T, the trainman restores switch 2W to its normal position, and replaces bow 22 of padlock 2P in its locking position, and then, without returning switch 1W to its normal position, attempts to move lever 3V to the normal position. With lever 1V in its reverse position, lug 14 attached to bar 6 at switch 1W will engage lug 15 which is attached to bar 7 of lever 1V when the trainman starts to return lever 3V to its normal position, and will thus prevent further movement of lever 3V toward its normal position. The trainman will then return switch 1W to its normal position by placing lever 1V in its *n* position.

I shall also assume further, however, that the trainman forgets to return bow 22 of padlock 1P to its locking position, and therefore contact 23

controlled by bow 22 remains closed, so that winding 1K is still energized. Armature 17 of winding 1K will therefore be in the energized position, shown in Fig. 2a, and will prevent the return of locking plunger 16 to its locking position, shown in Fig. 1, so that if, now, the trainman again attempts to return lever 3V to its *n* position, he will be prevented from doing so because of the engagement of locking plunger 16 with armature 17 in the position shown in Fig. 2a.

If the trainman now places bow 22 of padlock 1P in the locking position, thereby opening the associated contact 23, winding 1K will become de-energized, so that armature 17 will drop into its locking position, shown in Fig. 1. Lever 3V can then be returned to its *n* position.

The initial portion of the movement of lever 3V, from its *r* to its *n* position, opens contact 24, thereby deenergizing relays TE and TS. Further movement of lever 3V toward its *n* position returns blocking pieces 9 of bars 6 into position to lock levers 1V and 2V in the *n* position, and the final portion of the movement of lever 3V to its *n* position opens contacts 11 and 12 at switches 1W and 2W, thereby removing the shunts from tracks 1T and 2T, so that relays 1R and 2R again become energized and the portions of the signal circuits shown will become closed.

Operation of the form of apparatus shown in Fig. 2, for reversing switch 1W for a train to move from track 1T to track AT or in the opposite direction, is similar to the operation of the apparatus just described for Fig. 1. It is therefore believed that the operation of the form of apparatus shown in Fig. 2 can be readily traced without further detailed description. If contact 25, shown in the circuits for controlling relays TE and TS in Fig. 2, is operated in conjunction with lock bar 6, it will be closed only by the final movement of this lock bar toward the left, as shown in the drawing, by the movement of lever 3V to its *r* position. Derail D for auxiliary track AT is moved to its non-derailing position by lever IV in conjunction with the movement of switch 1W to its reverse position.

I shall assume that, with the form of apparatus shown in Fig. 3, a train is to move over track 3T. A trainman will first remove bow 22 of padlock 3P from its locking position, thereby effecting the closing of contacts 27, 28 and 29. Contacts 28 and 29, upon becoming closed, complete shunt paths across the rails of tracks 1T and 2T, causing relays 1R and 2R to be deenergized and open the circuits for controlling signals 1S and 2S.

At the same time, contact 27 completes a circuit for energizing relay TS, this circuit passing from battery Q, through contact 27, back contact 31 of relay TE, and the winding of relay TS, back to battery Q. Relay TS, upon becoming energized, completes its own stick circuit, which is the same as the pick-up circuit just traced except including its own contact 32 instead of contact 31 of relay TE. Relay TS, upon becoming energized, completes a circuit for energizing relay TE, passing from battery Q, through contact 27 operated by padlock 3P, contact 33 of relay TS and the winding of relay TE, back to battery Q. Relay TE, upon the lapse of a measured period of time, closes its contact 34, thereby completing a circuit for energizing lock winding 3K, this circuit passing from battery Q, through contact 27 operated by padlock 3P, contact 33 of relay TS, contact 34 of relay TE, and winding 3K, back to battery Q. Winding 3K, upon becoming energized, lifts its armature 17 out of

locking engagement with segment 18 associated with lever 3V.

The trainman will then reverse lever 3V. Lever 3V, during the initial part of this movement, effects the closing of contacts 11 and 12 at switches 1W and 2W, thereby placing additional shunts across the rails or track sections *a*—*b* and *c*—*d*. Further movement of lever 3V to its *r* position effects movement of bars 26 out of locking engagement with lock bars 13 of switches 1W and 2W and with levers 1V and 2V.

With switches 1W and 2W and levers 1V and 2V now unlocked, the trainman may reverse switch 1W by movement of lever 1V to its *r* position, and may reverse switch 2W by movement of lever 2V to its *r* position.

If, after a train has moved over crossover track 3T, a trainman returns switch 2W to its normal position and attempts to return lever 3V to its normal position without first returning switch 1W to its normal position, lock bar 26 associated with lever 1V cannot be returned to the notch in switch lock rod 13 and will therefore prevent the return of lever 3V to its *n* position. After lever 1V has been returned to its *n* position for moving switch 1W to its normal position, bar 26 can be moved into the notch in lock rod 13 and therefore lever 3V can be returned to its *n* position.

If, now, the trainman forgets to return bow 22 of padlock 3P to its locking position, contacts 28 and 29 operated by bow 22 will remain closed, and therefore sections *a*—*b* and *c*—*d* will continue to be shunted, causing signals 1S and 2S to continue to display the stop indication. When the trainman returns bow 22 of padlock 3P to its locking position, contacts 27, 28 and 29 controlled by bow 22 will again be opened, and hence relays TE and TS will be deenergized by contact 27, and the shunt paths across sections *a*—*b* and *c*—*d* will be open at contacts 28 and 29, thus permitting relays 1R and 2R to again become energized and close their contacts 30 in the circuits for signals 1S and 2S. All parts of the apparatus will then again be in the normal condition.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In traffic protection apparatus for a stretch of railway in which two main tracks are interconnected by a crossover track through two track switches one at each end of said crossover track, including a manually operable switch lever for each of said switches, each of said levers movable between normal and reverse positions for controlling the associated switch, and including a manually operable auxiliary lever which when placed in its normal position mechanically locks each of said switch levers in its normal position, the combination comprising, an electric lock for each of said switch levers which when deenergized locks its lever when its lever is in the normal position, locking means operable mechanically by said auxiliary lever for locking said electric locks only if both of said electric locks are in condition for locking said switch levers when said auxiliary lever is operated to its normal position, and means controlled by said auxiliary lever in a reverse position for energizing said electric locks and for retaining said electric locks

energized only while said auxiliary lever remains in said reverse position.

2. In traffic protection apparatus for a stretch of railway in which two main tracks are interconnected by a crossover track through two track switches one at each end of said crossover track, including a manually operable switch lever for each of said switches, each of said levers movable between normal and reverse positions for controlling the associated switch, and including a manually operable auxiliary lever which when placed in its normal position mechanically locks each of said switch levers in its normal position, the combination comprising, an electric lock for each of said switch levers which when deenergized locks its lever when its lever is in the normal position, locking means controlled by said auxiliary lever for mechanically locking said electric locks if both said switch levers are in the normal position and if both said electric locks are deenergized, and manually controllable means for energizing and afterward deenergizing said electric locks.

3. In traffic protection apparatus for a stretch of railway in which a main track is connected with an auxiliary track by a switch, including a manually operable switch lever movable between normal and reverse positions for controlling said switch, and including a manually operable auxiliary lever which when placed in its normal position mechanically locks said switch lever in its normal position, the combination comprising, an electric lock for said switch lever for locking said switch lever in the normal position when said electric lock is deenergized, locking means controlled by said auxiliary lever when operated to its normal position for locking said electric lock in its locking condition while said switch lever is in its normal position, and manually controllable means for energizing and afterward deenergizing said electric lock.

4. In traffic protection apparatus for a stretch of railway in which a main track is connected with an auxiliary track by a switch, including a manually operable switch lever movable between normal and reverse positions for controlling said switch, and including a manually operable auxiliary lever which when placed in its normal position locks said switch in its normal position, the combination comprising, an electric lock for said switch lever for locking said switch lever in the normal position when said electric lock is deenergized, means controlled by said auxiliary lever for at times mechanically locking said electric lock in its locking condition, and manually controllable means for energizing and afterward deenergizing said electric lock.

5. In traffic protection apparatus for a stretch of railway in which a main track is connected with an auxiliary track by a switch, including a manually operable switch lever movable between normal and reverse positions for controlling said switch, and including a manually operable auxiliary lever which when placed in its normal position locks said switch in its normal position, the combination comprising, an electric lock for said switch lever for locking said switch lever in the normal position when said electric lock is deenergized, means controlled by said auxiliary lever for mechanically locking said electric lock in its locking condition when said auxiliary lever is operated to its normal position, and means controlled by said auxiliary lever in its reverse position for energizing said electric lock and for retaining said electric lock energized only while

said auxiliary lever remains in said reverse position.

6. In traffic protection apparatus for a stretch of railway in which a main track is connected with an auxiliary track by a switch, including a manually operable switch lever movable between normal and reverse positions for controlling said switch, and including a manually operable auxiliary lever which when placed in its normal position locks said switch in its normal position, the combination comprising, an electric lock for said switch lever for locking said switch lever in the normal position when said electric lock is deenergized, means controlled by said auxiliary lever for locking said electric lock in its locking condition when said auxiliary lever is operated to its normal position, a time element relay, a stick relay, a pick-up and a stick circuit for said stick relay each controlled by a contact closed by said auxiliary lever in a reverse position and said pick-up circuit also controlled by a checking back contact of said time element relay, a circuit controlled by a front contact of said stick relay for energizing said time element relay, and a circuit controlled by a front contact of said stick relay and by a front contact of said time element relay for energizing said electric lock.

7. In traffic protection apparatus for a stretch of railway in which a main track is connected with an auxiliary track by a switch, including a manually operable switch lever movable between normal and reverse positions for controlling said switch, and including a manually operable auxiliary lever which when placed in its normal position locks said switch lever in its normal position, the combination comprising, an electric lock for said auxiliary lever for locking said auxiliary lever in the normal position when said electric lock is deenergized, a time element relay, a stick relay, a manually operable device, a pick-up and a stick circuit for said stick relay each controlled by said manually operable device and said pick-up circuit also controlled by a checking back contact of said time element relay, a circuit controlled by a front contact of said stick relay for energizing said time element relay, and a circuit controlled by a front contact of said stick relay in series with a front contact of said time element relay for energizing said electric lock.

8. In traffic protection apparatus for a stretch of railway in which a main track is connected with an auxiliary track by a switch, including a manually operable switch lever movable between normal and reverse positions for controlling said switch, and including a manually operable auxiliary lever which when placed in its normal position locks said switch lever in its normal position, the combination comprising, an electric lock for said switch lever which locks said switch lever if said switch lever is in the normal position when said electric lock is deenergized, locking means controlled by said auxiliary lever upon being moved from its reverse to its normal position for locking said electric lock in its locking position and said locking means controlled by said electric lock in its unlocked position for locking said auxiliary lever in its reverse position, and manually controllable means for energizing said electric lock.

9. In traffic protection apparatus for a stretch of railway in which a main track is connected with an auxiliary track by a switch, including a manually operable switch lever movable between normal and reverse positions for controlling said switch, and including a manually operable auxil-

iary lever which when placed in its normal position mechanically locks said switch lever in its normal position, the combination comprising, an electric lock for said switch lever which if deenergized locks said switch lever if said switch lever is in the normal position, mechanical locking means movable by said auxiliary lever for locking said electric lock in its locking position when said auxiliary lever is moved from its reverse to its normal position and said mechanical locking means controlled by said electric lock when in its unlocking position for retaining said auxiliary lever in its reverse position, and manually controllable means for energizing said electric lock.

10. In traffic protection apparatus for a stretch of railway in which a main track is connected with an auxiliary track by a switch, including a manually operable switch lever movable between normal and reverse positions for controlling said switch, and including a manually operable auxiliary lever which when placed in its normal position mechanically locks said switch lever in its normal position, the combination comprising, an electric lock for said switch lever which if deenergized locks said switch lever if said switch lever is in the normal position, mechanical locking means movable by said auxiliary lever for locking said electric lock in its locking position when said auxiliary lever is moved from its reverse to its normal position and said mechanical locking means controlled by said electric lock when in its unlocking position for retaining said auxiliary lever in its reverse position, a shunt path across the rails of said main track which is open while said auxiliary lever is in its normal position but which becomes closed by said auxiliary lever as soon as said auxiliary lever is moved out of its normal position and which remains closed while said auxiliary lever is being moved between its normal and reverse positions and while said auxiliary lever is in its reverse position, and manually controllable means for energizing and afterward deenergizing said electric lock.

11. In traffic protection apparatus for a stretch of railway track connected with a second track by a switch, the combination comprising, a manually operable switch lever having a normal and a reverse position for operating said switch to a normal and a reverse position respectively for traffic movements along said stretch of track and said second track respectively, a manually operable auxiliary lever having a normal and a reverse position, means controlled by said auxiliary lever in its normal position for locking said switch lever in its normal position, an electric lock which in its normally deenergized locking condition prevents operation of said switch lever away from its normal position, a manually operable contact having a normally open position and a closed position, a stick relay, a time element relay, a pickup and a stick circuit for said stick relay both controlled by said manually operable contact and said pickup circuit also controlled by a back contact of said time element relay, an energizing circuit for said time element relay controlled by said manually operable contact and by a front contact of said stick relay, and an energizing circuit for said electric lock controlled by front contacts of said stick and time element relays and also by said manually operable contact and retaining said

electric lock energized only while said manually operable contact is in its closed position.

12. In traffic protection apparatus for a stretch of railway track connected with a second track by a switch, the combination comprising, a manually operable switch lever having a normal and a reverse position for operating said switch to a normal and a reverse position respectively for traffic movements along said stretch of track and said second track respectively, an electric lock which in its normally deenergized locking condition prevents operation of said switch lever away from its normal position, a manually operable contact having an open position and a closed position, a stick relay, a time element relay, a pickup and a stick circuit for said stick relay both controlled by said manually operable contact and said pickup circuit also controlled by a back contact of said time element relay, an energizing circuit for said time element relay controlled by said manually operable contact and by a front contact of said stick relay, and an energizing circuit for said electric lock controlled by front contacts of said stick and time element relays and also by said manually operable contact and retaining said electric lock energized only while said manually operable contact is in its closed position.

13. In traffic protection apparatus for a stretch of railway track connected with a second track by a switch, the combination comprising, a manually operable switch lever having a normal and a reverse position for operating said switch to a normal and a reverse position respectively for traffic movements along said stretch of track and said second track respectively, a manually operable auxiliary lever having a normal and a reverse position, means controlled by said auxiliary lever in its normal position for locking said switch lever in its normal position, an electric lock which in its normally deenergized locking condition prevents operation of said auxiliary lever away from its normal position, a padlock for said electric lock, a first contact which is opened by the bow of said padlock when said padlock is applied to said electric lock but which becomes closed when said padlock is removed from its locking position in relation to said electric lock, a stick relay, a time element relay, a pickup and a stick circuit for said stick relay each controlled by said first contact and said pickup circuit also controlled by a back contact of said time element relay, a circuit controlled by said first contact and by a front contact of said stick relay for energizing said time element relay, and a circuit controlled by front contacts of said stick and time element relays and also by said first contact for energizing said electric lock.
